CLAIM

The ornamental design for a smart gateway, as shown and described.

DESCRIPTION

FIG. 1 is a perspective view of a smart gateway;
 FIG. 2 is a front elevational view of the smart gateway;
 FIG. 3 is a rear elevational view of the smart gateway;
 FIG. 4 is a left side elevational view of the smart gateway;
 FIG. 5 is a right side elevational view of the smart gateway;
 FIG. 6 is a top plan view of the smart gateway; and,
 FIG. 7 is a bottom plan view of the smart gateway.
 The broken lines in the drawings depict portions of the smart gateway that form no part of the claimed design.
